UNITED STATES PATENT OFFICE

152,220

DESIGN FOR A SLED

John L. Shailer, Roslyn, N. Y.

Application August 31, 1948, Serial No. 148,391

Term of patent 3½ years

(Cl. D34—15)

To all whom it may concern:

Be it known that I, John L. Shailer, a citizen of the United States, residing at Roslyn, in the county of Nassau, State of New York, have invented a new, original, and ornamental Design for a Sled, of which the following is a specification, reference being had to the accompanying drawing, forming part thereof, wherein the figure of the drawing is a perspective view of the sled showing my new design.

I claim:

The ornamental design for a sled, substantially as shown.

JOHN L. SHAILER.
